UNITED STATES PATENT OFFICE.

HENRY MAYER, OF ARBON, GUSTAV SCHLATTER, OF STEINACH, AND PAUL BOECKLY,
OF ARBON, SWITZERLAND, ASSIGNORS TO SOCIETE ANONYME ADOLPHE SAURER,
OF ARBON, SWITZERLAND, A CORPORATION OF SWITZERLAND.

DUMPING WAGON.

Application filed October 5, 1920. Serial No. 414,840.

To all whom it may concern:

Be it known that we, HENRY MAYER, of Arbon, Switzerland, GUSTAV SCHLATTER, of Steinach, Switzerland, and PAUL BOECKLY, of Arbon, Switzerland, respectively, all citizens of Switzerland, have jointly invented certain new and useful Improvements in Dumping Wagons, of which the following is a specification, reference being had to the accompanying drawings, forming a part hereof.

This invention relates to a dumping wagon in which provision is made for tilting the body towards either side or towards the rear for the purpose of discharging the contents. The invention has for its principal object to provide improved devices for effecting the tilting of the body selectively in the manner described and more particularly to provide a four-point bearing and hinge support for the body with devices co-operating with such bearing supports as will enable any two of them to be locked as hinge points while the other two are free for the tilting of the body in so far as may be necessary, to effect the tilting towards one side or the other or towards the rear. In carrying out this object of the invention the body is provided with ball and socket joints at four remote points which are adapted to be locked selectively in pairs to the wagon frame for the purpose of permitting the dumping operations described above. A feature of the invention, however, is that while the supporting joints are locked selectively in pairs, they are, as a matter of fact, connectible to and disconnectible from the frame as individual units.

A second object of the invention is to provide in a dumping wagon of the character described power operated devices for tilting the body and controlling means therefor which are positively locked against movement so long as the control elements of the supporting joints for the body are in certain predetermined positions.

A further feature of the invention consists of a sort of safety locking device controlled automatically by the wagon body to prevent manipulation of the locking devices for the supporting joints until the body rests in normal position at all four points of support on the wagon frame. This safety attachment prevents such manipula-

tion of the locking means for the supporting joints as would, perhaps, serve to uncouple more than two joints at one time and result in complete dislodgment of the body.

The invention will be described in sufficient detail with reference to the embodiment illustrated in the accompanying drawings, which drawings, while somewhat schematic in parts, will serve to illustrate the invention with sufficient clearness to one skilled in the art. In the drawings—

Figure 1 is a view in side elevation of a motor truck equipped with a dumping body having associated therewith the improved devices.

Figure 2 is a view in rear elevation of the truck shown in Figure 1.

Figure 3 is a plan view thereof.

Figure 4 is a view in rear elevation of the same truck indicating the side tilting positions of the body.

Figures 5 and 6 are views in longitudinal and transverse sections, respectively, through the shifting lever for the joint locks, one of the joint locks being illustrated in section in Figure 5.

Figure 7 is a detail view showing, partly in elevation and partly in section, the relation of the dumping body to the vehicle frame and two of the supporting joints for the body.

Figure 8 is a fragmentary view in horizontal section through the joints shown in Figure 7.

Figures 9 and 10 are views in perspective showing a control rod for the joints in different angular positions.

Figure 11 is a view in side elevation of the safety device controlled by the body for preventing axial movement of the shifting rod when the body is not completely seated on the frame.

In the illustrated embodiment the dumping body 1 is shown as supported at four points I, II, III, IV, on transverse sills 2 of the frame 3 of a motor vehicle. The body 1 preferably rests directly on transverse beams 4 adapted to extend in line respectively with the transverse sills 2 of the frame 3. At opposite ends of each of the beams 4 are formed supporting joints for the body, illustrated, in the preferred form, as ball and socket joints, comprising socket

2
 pieces 5 and ball pieces 6 retained therein by closing rings 8. The ball pieces 6 are preferably formed with flat webs 9 adapted to rest on upright supports 7 carried with 5 the transverse sills 2. Within each of the ball pieces 6 and overlying the web 9 is mounted a locking key 11 of a length less than the length of a slot 10 formed within the web 9 but greater than the width of said 10 slot. This key 11 can be rotated to register with the slot 10 so that the ball piece 6 can be moved from its support 7 or the key can be rotated to extend across said slot and lock the ball piece on such support. Each of the points of support I, II, 15 III, IV, for the body 1 is constructed in the manner described so that it will be clear that the body is supported by four hinge joints which are separately connectible to and disconnectible from the supporting frame of the vehicle.

One feature of the invention resides in hand operated means of a convenient character for locking the supporting joints selectively to the frame in pairs for the purpose of permitting the body to be tilted to one side or the other or to the rear as may be desired. Such devices include for each supporting joint a rotatable spindle 12 on 20 which the key 11 is carried, journaled in the support 7 and having at its lower end a bevel pinion 13 engaged by a bevel pinion 14 on the end of a transversely extending shaft 15 supported within the sill 2. As 25 indicated most clearly in Figure 7 the front joints I, II have shafts 15 which can conveniently be aligned but which are independent of one another, and Figure 3 indicates that the rear joints III, IV have their shafts 30 in similar relation.

Referring now to Figure 9 it appears that on the inner end of the operating shaft 15 for the points I, II, III, IV are secured swinging arms 48, 49, 50 and 51, respectively. The lower ends of these swinging arms 48, 49 are engaged operatively with a groove 45 in a collar 43 secured to a shifter rod 38, while the lower ends of the swinging arms 50, 51 are engaged operatively 45 with a groove 55 in a locking segment 53 through which the shaft 38 extends slidably. The collar 43 is interrupted to receive a locking segment 52 having a groove 54 in line with the groove 45, the segment 52 being loosely supported on the shaft 38. The locking segment 53 is interrupted to receive a segmental collar 44 which is secured to the shaft 38 and is formed with a groove 46 in line with the groove 55. As 50 shown in Figure 5 the segment 52 is mounted within a housing 42 which holds the segment against endwise movement upon axial movement of the shaft 38 with its collar 3. The segment 53 is likewise mounted 55 within a housing and held against axial

movement upon axial movement of the shaft 38 with its segmental collar 44. Accordingly, it will be clear that when the arms 48, 49 are engaged with the collar 43 the two shafts 15 controlling the respective keys 11 of the front bearing joints I, II will be rocked upon axial movement of the shaft 38. With the shaft 38 in this angular position the lower ends of the arms 50, 51 will be locked against movement by the segment 53, so that the keys 11 for the rear supporting joints III, IV cannot be released. Under these circumstances the body is in condition for rearward tilting. If, now, the shaft 38 be rocked in a counterclockwise direction, as shown in Figure 10, the locking segment 52 will be engaged with the lower end of the swinging arm 48 while the arm 49 will remain in operative engagement with the collar 43. Axial movement of the shaft 38 will thereupon cause the arm 49 to swing for actuation of its shaft 15 for the key 11 of the bearing II, while the other arm 48 with its associated elements will be locked against movement. Meanwhile the lower end of the arm 51 will be found engaged with the collar 44 while the lower end of the arm 50 will be found locked by the segment 53. This condition will bring about unlocking of the two right hand supporting joints II, IV, as viewed in Figure 3, while the two left joints I, III, will be held locked to the frame. In that condition the body can be tilted for dumping to the left as shown in Figure 4. If, now, it be desired to tilt the body to the right, as indicated in dotted lines in Figure 4, the shaft 38 will be rocked in a clockwise direction, as viewed in Figure 9, for the purpose of engaging the locking segment 52 with the lower end of the arm 49 and the locking segment 53 with the arm 51. Meanwhile the arm 48 will remain engaged with the collar 43 and the arm 50 will be engaged with the collar 44. Axial movement of the shaft 38 will thereupon swing the arms 48 and 50 to unlock the two left hand joints I, III, while the arms 49, 51 will be locked against movement by the segments 52, 53.

A further feature of the invention, which will be found of especial convenience in motor vehicles, resides in the provision of a convenient hand lever for controlling the shaft 38, adapted to be mounted within convenient reach of the driver's seat. This lever is shown at 29 and is adapted to be engaged operatively with the operating rod 38. One convenient means for affording this engagement is illustrated in Figures 5 and 6. As shown there, the lever 29 is pivoted on the pin 30 to the housing 31 which is pivotally supported on a shaft 32. The lower end 34 of the lever 29 is forked and engages a flanged hub 35 on the slidable shaft 11

- 32, one flange 36 of the hub extending downwardly and engaging the shaft 38. This shaft 38 extends into the housing 31 through a curved opening 39 which will permit the 5 housing to swing freely about its supporting shaft 32. The lower inner wall of the housing 31 is formed as a segment 40 with teeth adapted to be engaged by the teeth of a gear 41 carried with the shaft 38. Both the shafts 10 32 and 38 are journaled in fixed bearings 33 and 39. When the hand lever 29 is in its vertical position, as shown in Figure 6, and rocks rearwardly in the direction of the arrow, as shown in Figure 5, the supporting 15 shaft 32 will be slid longitudinally and will cause axial movement of the shaft 38 through the fork 36. In the median position of the operating lever 29 the parts will be in the position illustrated in Figure 9 20 and rearward dumping will be brought about. If now, the lever 29 is rocked to the left, as shown in Figure 6, it will swing with it the housing 31 about the shaft 32 as an axis, this rotative movement of the housing causing rotation of the shaft 38 through the 25 engagement of the segment 40 with the gear 41. This movement will rock the shaft 38 in a counterclockwise direction until the parts assume the position shown in Figure 30 10. The shaft 38 can then be slid axially by rocking the lever 29 in the usual manner. As pointed out before this will serve to rotate the keys 11 of the bearings II, IV for the 35 purpose of permitting the body to be tilted to the left as viewed in Figure 4. After the body is returned to normal position where it rests completely on its four supports the lever 29 can be rocked to move the shaft 38 axially and lock all of the keys 11. When 40 the lever 29 is rocked towards the right, as viewed in Figure 6, it is evident that the shaft 38 will be rocked in a clockwise direction as compared to its position in Figure 9, swinging movement of the lever 29 serving 45 further to effect the unlocking of the two left hand joints I, III, the joints II, IV remaining locked, for tilting of the body towards the right, as indicated in dotted lines in Figure 4.
- 50 The invention is not to be limited to the power devices for actually effecting the tilting of the body, but as shown in the drawings a fluid pressure cylinder 24 is mounted under the vehicle frame and receives an actuating medium through a supply pipe 27 for the actuation of a sliding piston 25 connected through a rod 26 to an arm 23 of a bell crank 21 connected respectively through links 18 to the arms 19 of a bell crank 55 secured to the underside of the body through a universal joint 20. With the power applied in the manner described, it is evident that the direction of tilting which the body will assume will depend entirely on which 60 pair of supporting joints is locked by the 65 keys 11. For instance, if the joints II, IV are locked and the joints I, III unlocked the body will tilt to the right; with the joints I, III locked and the joints II, IV unlocked the body will tilt to the left and with the joints III, IV locked and the joints I, II unlocked the body will tilt to the rear. All of this tilting will take place under the influence of power applied at the one point from the piston 25.
- 70 Another feature of the invention which may be of considerable importance has to do with the locking of the fuel control devices for the motor cylinder 24, so long as the control devices for the various locks of the joints are not in predetermined relation. It is quite evident that it is not desirable and, indeed, may be dangerous to permit the motor 24, 25 or its equivalent element, to 75 impress power upon the body 1 before the joints are unlocked in the desired combination. To prevent any such premature application of power it is proposed, in accordance with the invention, to mount the control lever 62 for the valve of the motor 24, 25 in such relation to the control lever 29 for the locking devices of the joints I, II, III, IV as to permit the lever 62 to be moved 80 only when the parts associated with the lever 29 are in predetermined position. Details of the precise means for carrying out this relation can be changed by one skilled in the art, but a suitable construction is illustrated in Figure 5. There, the lever 62 is mounted pivotally at 63 and by its movement controls the valve or other element for the motor 24, 25 or equivalent device. The lever 62 is formed as a bell crank and has its lower arm 64 normally resting against a quadrant 65 which is secured to a shaft 66 on 85 which is supported a lever arm 67. This arm has a slot and stud connection indicated at 68 with the end of the slideable shaft 32 upon which is supported the housing 31. So long as the lever 29 is in median position 90 power cannot be applied to the body since the quadrant 65 bears against the arm 64 of the control lever 62. When the lever 29 has been rocked so as to move the shaft 32 and control rod 38 to the position indicated 95 in dotted lines in Figure 5, it is certain, as hereinbefore explained, that two of the joints will be unlocked and two will remain locked. In this condition it is safe to apply power to the body to tilt it. With the shafts 32 and 38 in the position shown in dotted lines it will be clear that the arm 67 with the locking quadrant 65 will have been rocked 100 in a clockwise direction, so as to move the quadrant out of engagement with the end of the arm 64 and permit the fuel control lever 62 to be manipulated.
- 105 A further feature of safety may be provided in the form of the devices shown in Figure 11. The broad object of such de- 110
- 115
- 120
- 125
- 130

4

vices is to prevent the control rod 38 from being shifted so long as the body does not rest completely on its four supporting joints I, II, III, IV. It is evident that this is of considerable importance since otherwise the operator, having two of the joints unlocked, might manipulate the control lever 29 in such manner as to unlock the remaining two joints and cause considerable damage. The safety devices for the purpose just mentioned find embodiment in the present application in a simple lever 57, 60 pivoted on the frame of the vehicle at 56 and having one end adapted to be engaged by the body when the latter is in its normal position of rest and the other end engageable with spaced flanges 59 carried with the shaft 38. The lever 57 may be engaged operatively by a spring 58 which serves to engage its end with the flanges 59 when the body is moved out of engagement with the end 61. The operation of this simple lock will be apparent. When the body 1 is out of engagement with the end 61 of the lever 60, the opposite end 57 will be drawn into engagement with the flanges 59 of the rod 38 and lock the latter against further movement. None of the locking devices for the joints I, II, III, IV can therefore be manipulated until the body 1 is restored to normal position resting completely on the four supporting joints, whereupon it will trip the lock 57 and release the shaft 38 for actuation in the manner hereinbefore described.

35 We claim as our invention.

1. In a dumping wagon, the combination of a frame, a body detachably connected to one of said two named elements, four supporting joints for the body, and locking devices operable selectively to lock said supporting joints in pairs in position while unlocking the remaining two joints.

2. In combination, a supporting frame, a dumping body, four ball and socket joints to support the body carried with the body, and devices operable selectively to lock said joints to the frame in pairs while unlocking the other two joints for tilting of the body.

3. In combination, a supporting frame, a dumping body, four ball and socket joints carried with the dumping body and adapted to support it on the frame, locking keys engageable with said balls to lock them to the frame, separate shafts geared to said keys, and a single operating rod movable axially and angularly and intermediate connections to rotate said shafts and operate said keys in selective combinations of pairs for the purpose of locking certain of said keys while unlocking the others.

4. In combination, a supporting frame, a dumping body, four ball and socket joints carried with the dumping body and adapted to support it on the frame, locking keys engageable with said balls to lock them to the

frame, separate shafts geared to said keys, a single operating rod movable axially and angularly and intermediate connections to rotate said shafts and operate said keys in selective combinations of pairs for the purpose of locking certain of said keys while unlocking the others, and a hand lever operatively engaged with said rod for controlling its movements. 70

5. In combination with a frame, a dumping body, four ball and socket joints carried with the body and adapted to rest on the frame, keys to lock said joints to the frame, separate operating shafts for said keys, a single operating rod actuating said shafts, and devices carried with the rod and with the shafts and engageable selectively by rotation of the rod to effect actuation of the keys selectively for the purpose of locking certain of them and unlocking others of them. 75

6. In combination, a supporting frame, a dumping body, four ball and socket joints carried with the dumping body and adapted to support it on the frame, locking keys engageable with said balls to lock them to the frame, separate shafts geared to the said keys, a single operating rod movable axially and angularly and intermediate connections to rotate said shafts and operate said keys in 90 selective combinations of pairs for the purpose of locking certain of said keys while unlocking the others and power devices mounted on the frame and operatively connected to the body for tilting it. 95

7. In combination, a supporting frame, a dumping body, four ball and socket joints carried with the dumping body and adapted to support it on the frame, locking keys engageable with said balls to lock them to the frame, separate shafts geared to said keys, a single operating rod movable axially and angularly and intermediate connections to rotate said shafts and operate said keys in 105 selective combinations of pairs for the purpose of locking certain of said keys while unlocking the others, a hand lever operatively engaged with said rod for controlling its movements, power devices mounted on the frame and connected to the body for 110 tilting it, and operating means for said power devices operatively engaged with said control lever and locked against movement by said lever so long as it remains in predetermined position. 115

8. In combination, a supporting frame, a dumping body, four ball and socket joints carried with the dumping body and adapted to support it on the frame, locking keys engageable with said balls to lock them to the frame, separate shafts geared to said keys, a single operating rod movable axially and angularly and intermediate connections to rotate said shafts and operate said keys 125 in selective combinations of pairs for the 130

purpose of locking certain of said keys while unlocking the others, power devices for tilting the body, means to control the operation of the power devices, and locking means therefor operable to release the power control devices only upon unlocking of certain of said keys.

5 joints for the body carried with one of said parts, locking devices operable selectively to lock said supporting joints in pairs to the other of said parts while unlocking the remaining two joints, and a single power device operatively connected with the body to tilt it in any direction depending upon 55 selection of locked and unlocked joints.

10 9. In combination, a supporting frame, a dumping body, four supporting joints carried with one of said two named elements, keys to lock said joints to the other of said two named elements, an actuating rod and intermediate connections for locking and 15 unlocking said keys selectively, separate operating shafts for said keys alined in pairs and having swinging arms secured thereto, a collar secured to said rod and engageable with the arms of two of the alined shafts, a segment with which the rod is mounted in 20 slidable relation and adapted to be engaged with one or the other of said last named arms, a second collar carried with the rod, and a second segment mounted in slidable relation thereto, said last named 25 collar and segment being engageable selectively with the arms of the other two alined shafts.

14. The combination with a chassis, of a tilting body adapted for side and end 70 dumping, means for locking each side and one end of the body with the chassis, and manually operable controlling mechanism for selectively releasing the locking means for permitting side or end tilting action 75 of the body.

15. In a vehicle of the character described, a frame, a tilting box turnable about either longitudinal side of said frame and the rear end thereof, a hand operable 80 lever, means for yieldingly holding said hand operable lever in three different positions, means on both sides and the rear end of said frame for locking and releasing the tilting box, and selective means between the 85 hand operable lever and said locking and releasing means and positively controlled by said lever to allow the tilting of the box at either side or the rear end of the frame.

90 This specification signed this 17th day of September A. D. 1920.

HENRY MAYER.
GUSTAV SCHLATTER.
PAUL BOECKLY.

10 10. In combination with a frame, a dumping body, four joints carried with one of said two named elements for the support of the body on the frame, keys to lock said joints selectively in position, an actuating rod operatively connected to said keys, and means controlled by the body for locking the rod against movement when the body is not resting on all four of said joints.

11. In combination, a frame, a dumping body, four supporting joints carried on the body, keys co-operating therewith to lock the joints to the frame, an actuating rod and intermediate connections for moving said keys selectively, and a spring-pressed locking lever co-operating with the rod and controlled by the body to lock the rod against movement when one of said joints is out of engagement with said frame.

12. In a dumping wagon, the combination of a frame, a body, four supporting
